(57) **CLAIM**

I claim the ornamental design for a bakeware set, as shown and described.

DESCRIPTION

This Non-Provisional Design Patent Application is related to U.S. design patent application Ser. No. 29/791,751, filed contemporaneously herewith on Feb. 4, 2022, entitled "Two-Sided Pan," the entire contents of which is hereby incorporated herein by reference.

FIG. 1 is a front, left, top perspective view of a bakeware set showing my new design;

FIG. 2 is a left elevation view thereof, the right elevation view being a mirror image thereof;

FIG. 3 is a front elevation view thereof, the rear elevation view being a mirror image thereof;

FIG. 4 is a top plan view thereof;

FIG. 5 is a bottom plan view thereof;

FIG. 6 is an exploded view thereof; and

FIG. 7 is a cross-sectional view of the section shown in FIG. 1;

FIG. 8 is a front, left, top perspective view of a bakeware set according to a second embodiment with handles, showing our new design;

FIG. 9 is a left elevation view thereof, the right elevation view being a mirror image thereof;

FIG. 10 is a front elevation view thereof, the rear elevation view being a mirror image thereof;

FIG. 11 is a top plan view thereof;

FIG. 12 is a bottom plan view thereof;

FIG. 13 is an exploded view thereof; and,

FIG. 14 is a cross-sectional view of the section shown in FIG. 8.
